UNITED STATES PATENT OFFICE.

WILLIAM D. WEAVER, OF HILLSVILLE, PENNSYLVANIA.

SCREW DRIVER.

Application filed December 23, 1926. Serial No. 156,634.

The present invention relates to tools and more particularly to screw drivers and has for its prime object to provide a tool shank associated with a handle so that said shank 6 may be placed in an extension of the handle and when in such position is prevented from rotation in respect to the handle or may be placed at right angles to the handle and when in this position is free to rotate in one 10 direction through an improved ratchet mechanism.

Another very important object of the invention lies in the provision of a tool of this nature which will have all the advantages 15 of an ordinary screw driver and an ordinary ratchet screw driver and one in which the shank of the tool may be disposed angularly to the handle so that the same may be used in close quarters and under other circumstances where the ordinary screw driver 20 could not be used to advantage.

A still further very important object of the invention lies in the provision of a tool of this nature which is comparatively simple 25 in its construction, exceedingly easy to manipulate and adjust, one which is thoroughly efficient and reliable in operation and use and otherwise well adapted to the purpose for which it is designed. With the above 30 and numerous other objects in view as will appear as the description proceeds, the invention resides in certain novel features of construction, and in the combination and arrangement of parts as will be hereinafter 35 more fully described and claimed.

In the drawing:

Figure 1 is an elevation of a tool embodying the features of my invention,

Fig. 2 is an other elevation thereof at 40 right angles to that shown in Figure 1,

Fig. 3 is a view similar to Fig. 2 but showing the shank of the tool at right angles to the handle,

Fig. 4 is a detail sectional view taken substantially on the line 4-4 of Fig. 1,

Fig. 5 is a detail view taken substantially on the line 5-5 of Fig. 3.

Referring to the drawing in detail, it will be seen that the numeral 5 denotes a handle 50 which has a detachable section 6 of tubular formation with outwardly diverging wings or extensions 7 fixed to the handle 5 by suitable fastening elements 8. From the other end of the tubular member 6 there extends 55 a pair of spaced parallel arms 9.

The numeral 10 denotes a shank which,

in the present instance, has a screw driver blade 11 at one end thereof while the other end is enlarged to form a head H of substantial cylindrical formation having longitudinally extending peripheral grooves 12 forming teeth and an annular and centrally formed groove 14 in which is rotatable a frame 15. This frame 15 is rotatably mounted between the extremities of the 60 arms 9 by rivets 16 or other suitable means. The extremity of the head 8 has a tongue 17 extending therefrom. A plunger 18 is slidable on the tubular member 6 and is pressed outwardly therefrom by 65 a spring 19. The outer end of the plunger is formed with a head 20 having a ratchet tooth 21 extending diametrically across the end face thereof and formed with a diametrically extending groove disposed at 70 right angles to the ratchet tooth 21.

When the screw driver blade is to be used under ordinary circumstances the shank 10 is disposed in extension of the handle as shown in Figs. 1 and 2, at which time the tongue and groove 17 and 22 respectively are engaged as is clearly shown in Figure 4 so that the shank is keyed to the handle and will rotate therewith in either direction. If it is desired to use the tool as a ratchet 80 screw-driver with the shank at right angles to the handle, the operator grasps the head 20 between the fingers and presser the plunger 18 inwardly thereby compressing the spring 19 and then moves the shank 10 to a right 85 angular position in either direction depending upon whether the screw is to be tightened or loosened as will be quite apparent. Supposing that the screw is to be tightened it will be seen that the shank is to be moved to the position indicated in Figs. 3 and 5 which causes the frame 15 to move from the plane shown in Figs. 1 and 2 to the plane shown in Figs. 3 and 5. The head 20 will 90 then engage with the piece on the head 8 and the ratchet tooth 21 will allow the screw driver blade to be rotated in a clockwise direction but when the handle is swung in a counter-clockwise direction, the ratchet tooth will slip over the head as will be apparent 95 from an inspection of Figure 5. Obviously, if the shank is disposed in the other direction the reversed ratcheting operation will take place and will be clear.

From the above detailed description it will 100 be seen that I have devised an exceedingly compact and convenient tool structure that is

handy, easy to manipulate, and thoroughly efficient and reliable. The structure is simple, strong and durable, and capable of being manufactured at a reasonably low cost.

5 The edge of the head 20 is provided with notches 20' to receive the arms 9 thus preventing rotation of the plunger 18 and its head 20 in respect to the handle.

It is thought that the construction, operation, utility, and advantages of this invention will now be apparent to those skilled in this art without a more detailed description thereof. The present embodiment of the invention has been disclosed in detail merely 15 by way of example since in actual practice it has attained the features of advantage enumerated as desirable in the statement of the invention and the above description.

It will be apparent that changes in the 20 details of construction, in the sizes, and in the combination and arrangement of parts may be resorted to without departing from the spirit or scope of the invention as hereinafter claimed or sacrificing any of its advantages.

Having thus described my invention what I claim as new:—

1. A tool of the class described including a handle having a tubular extension terminating in a pair of spaced parallel arms, a 30 tool shank having a cylindrical head at one

end, said head being formed with an annular groove intermediate its ends and longitudinally extending grooves forming teeth and a tongue extending from the extremity thereof, a frame rotatable in the annular groove, means for pivoting the frame between the arms, a spring pressed plunger in the tubular extension and formed with a head having a groove to receive the tongue and a ratchet tooth for association with the teeth of the head of the shank.

2. A tool of the class described comprising a handle, a tool shank provided with an annular groove and an annular series of ratchet 45 teeth adjacent the groove, a non-circular tongue extending coaxially from one end of the shank, a frame in the groove and rotatable about the shank, means for pivoting the frame to the handle, a plunger, means 50 for slidably mounting the plunger on the handle, one end of the plunger being provided with a non-circular socket, and spring means urging the plunger so that said one end thereof engages the teeth when the shank is disposed at an angle to the handle, or so that the socket of said one end of the plunger receives the tongue when the shank is in extension of the handle.

In testimony whereof I affix my signature.

WILLIAM D. WEAVER.
